UNITED STATES PATENT OFFICE.

BOHN CHAPIN HICKS, OF MINNEAPOLIS, MINNESOTA, ASSIGNOR, BY MESNE ASSIGNMENTS, TO THE HICKS STOCK CAR COMPANY, OF CHICAGO, ILLINOIS.

CHAIN FOR FLEXIBLE PARTITIONS.

SPECIFICATION forming part of Letters Patent No. 430,949, dated June 24, 1890.

Application filed November 12, 1889. Serial No. 329,982. (No model.)

To all whom it may concern:

Be it known that I, BOHN CHAPIN HICKS, a citizen of the United States, residing at Minneapolis, in the county of Hennepin and State of Minnesota, have invented certain new and useful Improvements in Flexible Partitions, of which the following is a specification.

This invention relates to the construction of flexible belts or partitions—such, for example, as are employed on stock-cars for dividing it into stalls or compartments; and the invention consists in the specific construction thereof.

The improved construction is illustrated in the accompanying drawings, wherein—

Figure 1 is a vertical cross-section of a partition constructed in accordance with the present invention. Fig. 2 is a similar view of the same, showing it rolled up; and Figs. 3 and 4 are enlarged detail views.

The improved flexible partition is composed of a plurality of cross-bars connected together at their ends by what may be termed “linked chains.” The main bar-supporting links of the chain are formed in two parts A' A², each part having an eye a on one end and adapted to be secured on opposite sides of the slats or bars B, forming the flexible partition, by bolts or rivets b, and with the eyes a on opposite edges of the bars B, as shown. The ends in which the eyes a occur are formed with square shoulders e', against which the edge faces of the cross-bar seat, these shoulders projecting beyond the bars, and also forming supports or abutments for the ends e² of the opposing parts of the link A' or A², as shown. The ends of the parts A' A² are extended beyond the shoulders e' and provided with lips e³, fitting into corresponding cavities in the adjacent parts of the opposite link, as shown,

whereby an additional bearing-surface is secured for the parts, and a portion of the end strains borne by the lips e³ instead of entirely by the bolts b. This is an important feature of my invention and greatly strengthens the union between the parts and equalizes the strains to which they are subjected. The two parts A' A² thus entirely encompass the bars B and combine the advantages of a strap or support for the bars with their use as links

of a chain, by which a number of the bars may be connected to form a flexible partition.

The eyes a of the two parts of each bar-supporting link are in a line parallel with the side faces of the cross-bar which is supported by the link. Preferably, and as shown, the centers of the eyes are in a line extending centrally through the cross-bar.

Links D are shown connecting the eyes a of one link with the adjacent ones, by which the partition may be extended to any desired length.

In the drawings I have shown the partition connected by a chain E to a shaft F', having one or more disks F², in which position it will be employed in a stock-car, this construction enabling the partition to be easily and readily rolled upon the disks F² as a roller or drum, as shown in Fig. 2. No claim is here made to this mechanism for rolling the flexible partition, such mechanism constituting the subject-matter of an application for Letters Patent of the United States No. 329,611, filed by me November 8, 1889.

The outer surfaces of the parts A' A² are slightly concaved, as shown, so that they will more readily adapt themselves to the curvature of the disks F² when being rolled up.

Another important advantage gained by this construction is that in event of the breakage of one of the bars B it may be readily removed and replaced by a new bar without disturbing the remaining bars.

Under some circumstances the parts A' A² of one bar B may be coupled directly to the corresponding parts of the adjacent bar without the interposed links D; but this would be substantially the same construction as shown.

Having thus described my invention, what I claim as new is—

1. A flexible belt or partition consisting of a plurality of cross-bars and bar-supporting links, each bar-supporting link being composed of two similar parts A' A², which are placed on opposite sides of one of the cross-bars, each part A' A² having an eye a, for pivotally connecting it to another link, and each part having a shoulder against which an edge-face of the cross-bar seats, substantially as set forth.

2. A flexible belt or partition consisting of a plurality of cross-bars and bar-supporting links, each bar-supporting link being composed of two similar parts $A' A^2$, which are placed on opposite sides of and embrace one of the cross-bars, each part having a square shoulder against which an edge face of the cross-bar seats, and each part having an eye a , for pivotally connecting it to another link, 5 to the two eyes a on the two parts of the same link being in a line parallel with the side faces of the cross-bar, substantially as set forth.
3. A flexible belt or partition consisting of a plurality of cross-bars and bar-supporting links, each bar-supporting link being com- 10 15

posed of two similar parts $A' A^2$, which are placed on opposite sides of and embrace one of the cross-bars, each part having a square shoulder against which an edge face of the cross-bar seats, and each part having a locking-lip e^3 and cavity e^2 , the locking-lip e^3 on one part engaging the cavity e^2 on the other part, substantially as set forth. 20

In testimony whereof I have hereunto set my hand in the presence of two subscribing 25 witnesses.

BOHN CHAPIN HICKS.
